UNITED STATES PATENT OFFICE.

MOSE MARKS, OF OMAHA, NEBRASKA, ASSIGNOR TO THE OMAHA SADDLE-TREE COMPANY, OF SAME PLACE.

DESIGN FOR A SIDESADDLE-FORK.

SPECIFICATION forming part of Design No. 32,442, dated April 3, 1900.

Application filed March 6, 1900. Serial No. 7,603. Term of patent 7 years.

To all whom it may concern:

Be it known that I, MOSE MARKS, a citizen of the United States, residing at Omaha, in the county of Douglas and State of Nebraska, have invented and produced a new and original Design for Sidesaddle-Forks, of which the following is a specification, reference being had to the accompanying drawing, forming part thereof.

10 The drawing is a perspective view of the fork of a sidesaddle, showing my new design.

As shown in the drawing, the leading or material feature of my design consists of a central portion A, from which on one side extends a substantially-horizontal swelled portion B, and from the other side of which extends a substantially-vertical curved portion

C. On the inner side of the portion B is a shoulder D, extending from which is a flat portion E, and extending downwardly from the portion B is an inclined flat portion F. Extending downwardly from about the junction of the part A with the part C is a flat inclined portion G, and extending upwardly from the outer surface of the part G is a curved portion H.

I claim as my invention—

The design for a sidesaddle-fork as herein shown and described.

MOSE MARKS.

In presence of—

JOHN STEINERT,
A. C. ASH.
